George W. Richards
ATTORNEY

UNITED STATES PATENT OFFICE

HARRY C. SCHICK, OF MADISON, NEW JERSEY

NECKLACE CLASP

Application filed May 2, 1931. Serial No. 534,510.

This invention relates, generally, to clasps; and the invention has reference, more particularly, to a novel necklace clasp adapted to be used interchangeably for either single, double or multiple strand necklaces or the like.

Necklace clasps as heretofore generally constructed, are designed to have one or more necklace strands permanently attached thereto. In other words, if a clasp were designed to have a single necklace strand or string attached thereto, it is only possible to use the clasp with that particular strand which was secured thereto at the time of the manufacture of the necklace. If the wearer should desire to use a strand of different color or character, it is necessary to either purchase an entirely new necklace or else to entirely restring the single strand necklace. Heretofore, it has been impossible to convert a single strand necklace into a multiple strand necklace or vice versa. Also, it has been impossible heretofore to convert a two strand necklace into a three strand necklace or to interchange the strands of a multiple strand necklace.

The principal object of the present invention is to provide a novel necklace clasp which is adapted to interchangeably receive either one or a plurality of necklace strands, the said necklace clasp presenting an extremely attractive appearance when the same has either a single strand attached thereto or a plurality of strands attached thereto, the said necklace clasp appearing to be solely designed to connect the number of strands it may happen to connect at any given time.

Another object of the present invention lies in the provision of a novel necklace clasp having a plurality of catch receiving openings therein adapted to interchangeably receive the catches of different necklace strands.

Still another object of the present invention is to provide a necklace clasp of simple construction, which is so constructed and arranged as to adapt the same for interconnecting varying numbers of interchangeable necklace strands, which necklace

strands may be of varying colors or color combinations or styles, depending upon the desire of the wearer.

Other objects of this invention not at this time more particularly enumerated, will be clearly understood from the following detailed description of the same.

The invention is clearly illustrated in the accompanying drawings, in which:—

Fig. 1 is a plan view illustrating the novel necklace clasp of this invention employed for connecting three necklace strands.

Fig. 2 is a fragmentary view illustrating the necklace clasp employed for connecting a single strand necklace.

Fig. 3 is a view similar to Fig. 2 but illustrates the necklace clasp used for connecting a double strand necklace.

Fig. 4 is an enlarged sectional view taken along line 4—4 of Fig. 1.

Fig. 5 is an enlarged sectional view taken along line 5—5 of Fig. 3.

Fig. 6 is a sectional view taken substantially along line 6—6 of Fig. 5.

Fig. 7 is a perspective detail view of a typical catch member; and

Fig. 8 is an enlarged sectional view taken along line 8—8 of Fig. 3.

Similar characters of reference are employed in all of the above described views, to indicate corresponding parts.

Referring now to the said drawings wherein the novel necklace clasp of this invention is illustrated, the reference numeral 1 designates a hollow body or casing having a cover 2 formed integrally therewith or otherwise secured thereto. Cover 2 is illustrated as provided with fretwork 2' giving this cover the appearance of an ornamental plaque. The casing 1 is illustrated as of rectangular shape, although it is to be understood that this casing may have any other desired shape, such as oval, round or the like. The side walls 3 and 4 of casing 1 are illustrated as provided with a plurality of spaced apertures 5 which are so shaped as to receive catch members 6 for interlocking engagement therewith. Each side wall 3 and 4 is illustrated in the drawings as provided with three of the apertures 5, al-

though it will be understood that a greater or lesser number of these apertures may be provided, as desired. Each of the end walls 7 and 8 of the casing 1 is illustrated as provided with a single aperture 5 for receiving a catch member 6.

The catch member 6 has a spring tongue 9 provided with stop shoulders 10 for engaging in stopped relation against the inner surface of the casing 1. A tab 11 formed on the free end of spring tongue 9 serves as a finger piece for use in inserting or removing the catch member from the casing 1. With the catch members 6 inserted into the apertures 5 of side walls 3 and 4, each pair of opposing catch members is adapted to be connected to the ends of a respective strand of beads. Thus, in Fig. 1, the lowermost pair of opposing or oppositely disposed catch members 6 are connected to the ends of a strand of beads 12. The intermediate pair of oppositely disposed catch members 6 are connected respectively to the respective ends of a strand of beads 13. The upper oppositely disposed pair of catch members in turn are respectively connected to the respective ends of a strand of beads 14. As especially shown in Fig. 5, it will be noted that with the oppositely disposed catch members 6 of a string of beads inserted into opposite apertures 5 in the side walls 3 and 4, one of the catch members overlies the other within casing 1. In this way the casing 1 may be made relatively narrow and attractive in appearance.

Should it be desired to obtain a two strand necklace, it is merely necessary for the wearer to disconnect one of the strands of beads from the casing 1. Thus, by disconnecting the catch members 6 of the strand of beads 13 from the casing 1, illustrated in Fig. 1, a two strand necklace shown in Fig. 3, is obtained. If it is desired to obtain a single strand necklace, the two strands of beads of Fig. 3 may all be disconnected from the casing 1 and the desired strand may have its catch members inserted into the apertures 5 provided in the end walls of casing 1 as illustrated in Fig. 2. In this way the wearer may use the same necklace clasp for use with a three strand, a two strand or a single strand necklace. It will be apparent that if the side walls 3 and 4 have additional apertures 5 therein, then additional strands of beads may be worn by the wearer so that any desired number of strands of beads may be thus connected by the clasp.

It will be apparent that by employing the novel necklace clasp of this invention, unlimited diversification of necklaces may be obtained. Thus, it will be apparent that not only may the number of strands be varied, but the arrangement and color combinations of the strands may be varied or interchanged as desired. Should the wearer

possess a multiplicity of bead strands similar to strands 12, 13 and 14, she may vary the color combination or appearance every day of the week, so that each day she will have a different necklace to wear while at the same time using but a single clasp. It will be noted that if the wearer should have, for example, fifteen or twenty-five necklace strands, the combinations are practically unlimited not only as to color and number but as to disposition of the various strands. Also, pendants or similar effects may be readily attached to the novel clasp of this invention. In other words, by using the clasp of the present invention, substantially unlimited diversification and interchangeability of bead strands or the like may be obtained as will be apparent by the simple expedient of disconnecting one or more strands and substituting another strand or strands therefor, which may be done with great ease and rapidity.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A necklace clasp comprising, a clasp body for connecting one or a plurality of necklace strands, said clasp body having a plurality of pairs of substantially oppositely disposed catch receiving apertures therein, and resilient catch members for attachment to the ends of necklace strands, said catch members being subject to interchangeable secured engagement in said pairs of catch receiving apertures.

2. A necklace clasp comprising, a clasp body, said clasp body having a plurality of similar catch receiving apertures in the side walls thereof, and a plurality of similar necklace strand catch members for interchangeably engaging in said catch receiving apertures, said catch members being arranged in pairs for connection to the ends of respective interchangeable necklace strands.

3. A necklace clasp for interchangeably connecting bead strands comprising, a hollow body having a bottom, side walls and end walls, and ornamental cover for said body, said body being provided with a plurality of spaced catch receiving apertures in the walls thereof, each aperture of one body wall being arranged in opposition to an aperture in the opposite body wall, and catch members adapted for interchangeable engagement in said catch receiving apertures, each pair of catch members engaged in two oppositely arranged catch receiving

apertures being adapted for connection to the ends of a respective strand of beads.

4. A necklace clasp for interchangeably connecting bead strands comprising, a hollow body having a bottom, side walls and end walls, an ornamental cover for said body, said body being provided with a plurality of spaced catch receiving apertures in the walls thereof, each aperture of one body wall being arranged in opposition to an aperture in the opposite body wall, and catch members adapted for interchangeable engagement in said catch receiving apertures, each pair of catch members engaged in two oppositely arranged catch receiving apertures being adapted for connection to the ends of a respective strand of beads, one of the catch members of each such pair being superimposed upon the opposing catch member of such respective pair within said hollow body.

5. A necklace clasp for interchangeably connecting bead strands comprising, a hollow substantially rectangular body having side and end walls, an ornamental cover for said body, the side walls of said body being provided with a plurality of pairs of oppositely disposed catch receiving apertures, the end walls of said body being provided with a single pair of oppositely disposed catch receiving apertures, and a plurality of pairs of catch members adapted to be engaged in said opposite catch receiving apertures of said body, each pair of catch members being adapted to be connected to the ends of a respective bead strand, said necklace clasp being adapted to serve as a multiple strand clasp when a plurality of pairs of catch members are engaged in the apertures of the side walls thereof and serving as a single strand clasp when a pair of catch members are engaged in the apertures of the end walls thereof.

In testimony, that I claim the invention set forth above I have hereunto set my hand this 30th day of April, 1931.

HARRY C. SCHICK.
